STENCIL LETTERING CARD

Robert S. Libauer, Baltimore, Md., assignor to Stenso
Lettering Company, Baltimore, Md., a firm

Application January 19, 1959, Serial No. 54,232

Term of patent 14 years

(Cl. D52—6)

The figure on the drawing is a plan view of a stencil lettering card showing my new design as it appears against a black background.

I claim:

The ornamental design for a stencil lettering card, substantially as shown.
